United States Patent Office

Des. 196,935
Patented Nov. 19, 1963

196,935

COMBINED KEY BLANK DISPENSER AND CUTTER

Nathan Weiner, 245 Puritan Road, Swampscott, Mass., and Irving Marcus, 47 Iroquois Road, Arlington, Mass.

Filed June 20, 1961, Ser. No. 65,654

Term of patent 7 years

The undisclosed side and rear of the article are substantially plain in appearance.

We claim:

The ornamental design for a combined key blank dispenser and cutter, substantially as shown and described.
